UNITED STATES PATENT OFFICE

113,369

DESIGN FOR A COMBINED DRILL PRESS HEAD AND MOTOR

Lewis S. Stump, Toledo, Ohio, assignor to William
B. Boice and John B. Boice, both of Toledo,
Ohio

Application December 16, 1938, Serial No. 81,826

Term of patent 14 years

Be it known that I, Lewis S. Stump, a citizen of the United States, residing in Toledo, in the county of Lucas and State of Ohio, have invented a new, original, and ornamental Design for a Combined Drill Press Head and Motor, of which the following is a specification, reference being had to the accompanying drawings, forming a part thereof, and in which:

Figure 1 is a side elevational view of a combined drill press head and motor showing my new design.

Figure 2 is a view of the other side thereof on a slightly reduced scale; and

Figure 3 is a front elevational view thereof on a slightly reduced scale.

I claim:

The ornamental design for a combined drill press head and motor, as shown.

LEWIS S. STUMP.
